FUSEE HOLDER

Gustav S. Krafft, Santa Maria, Calif.

Application June 2, 1951, Serial No. 229,556

1 Claim. (Cl. 279—29)

1

My invention relates to handles or grips; and a principal object of the invention is to provide a grip or holder for fusees to facilitate their safe, economical and efficient use.

Another object of the invention is the provision of a utility safety tool of special usefulness to railway brakemen.

The invention possesses other objects, some of which with the foregoing will be brought out in the following description of the invention. I do not limit myself to the showing made by the said description and drawings, since I may adopt variant forms of the invention within the scope of the appended claim.

Referring to the drawings:

Fig. 1 is a sectional view of my complete fusee holder. The section is taken on the long central vertical axis of the holder.

Fig. 2 is an elevation, partly in vertical section, showing the parts when a fusee is gripped in the holder.

Fig. 3 is a cross sectional view taken in the plane 3—3 of Fig. 1; and Fig. 4 is a cross sectional view taken in the plane 4—4 of Fig. 1.

Fig. 5 is a top or plan view taken in the direction indicated by arrow 5 in Fig. 1.

Fusees have long been used for railway signaling. Commonly, the fuel for the flare is arranged in a paper or pulp board cylindrical casing so loaded as to leave one end as a sort of grip by which the fusee may be handled. Experience over the years shows that railway brakemen and others using these flares are apt to receive painful and sometimes disabling burns on the hands and other parts of the body because of an uncontrolled flare; and burned and ruined gloves and clothing are even commoner results. There is of course an inherent danger in the use of such an implement, which is beyond all provisions of care, but danger of injury and damage can be reduced drastically by providing an efficient handle in which the fusee may be carried. This is the primary purpose of my invention, but I find it also possible and very desirable to make my fusee handle or holder of such shape and character as to constitute a utility tool for the brakeman confronted with a stuck or sluggish knuckle in making a coupling between two cars. In such a situation, loosening and opening the knuckle easily and quickly becomes of prime importance. Use of the hands directly is extremely dangerous. My device is shaped to permit its insertion in the casing hole so that it then serves as a handle and lever by which the knuckle may be moved and the coupling completed with safety.

2

With reference now to the drawings, my fusee holder comprises a hollow cylindrical head including a socket 2 in which the safe end of a fusee 3 may be inserted. The head is extended 5 in a tapered and preferably knurled handle 4, which serves several purposes in the use of my device as a utility tool. When used as a fusee holder the tapered extension 4 provides a convenient handle for the socket; and also, because it is hollow, a chamber 6 in which a portion of the mechanism is arranged.

When cars are to be coupled, the brakeman finds the tapered handle a convenient pin with which to engage the knuckle and move it with 15 safety to his hands.

Means are provided in the socket for releasably latching the fusee therein, and for ejecting the burned out fusee without touching it with the hands. The socket is structurally composed of 20 two cylindrical sections 7 and 8, the latter continuous with the handle 4, and held in spaced alignment by the outside shell 9 secured to both sections by small screws 12.

The two adjacent edges of the spaced sections 25 lie in divergent planes, as shown, with the edge 13 of the inner section 8 lying in a plane at 90° to the long central axis of the device, and the edge 14 of the outer section 7 lying in a plane biased across the axis at about 18° to the other plane. There is thus provided between the sections and within the shell, a space for the operation of the latch ring 16, normally held against the biased edge 14 by the spring-pressed rods 17, as shown in Fig. 1. The internal diameter of the latch ring is substantially the same 30 as that of the socket.

When the safe end of the fusee is pushed into the socket, it encounters the ring. Continued pressure pushes the ring down against the spring-pressed rods 17, to a position near or against the edge 13. At this point the latch is more or less aligned with the rest of the socket, and therefore permits the fusee to pass through it to the maximum penetration desired, the spring-pressed rods 40 however always tending to bias the latch ring so that any separating force is resisted by the lower edge 18 of the ring biting into the side of the fusee casing.

Means for releasing the latch are provided by 45 the slide 21, mounted within a long bead 22 pressed out from the shell. A button 23 on the slide extends through a slot in the bead so that the slide may be moved by the thumb of the holding hand. A lug 24 on the end of the slide 50 engages the upper edge of the latch ring, so that

moving the slide back toward the handle pulls the ring flat upon the edge 13 (the unbiased position) at which point the bite of the ring on the fusee case is released, and the fusee is freely movable in and out of the socket.

Means are provided for ejecting the burned-out fusee without need for touching it with the hands. Slidably disposed in the socket and handle is a plunger preferably comprising a central stem 26 with two spaced flanges 27 and 28, loosely fitting the cylindrical bore 29 in that part of the handle next to the socket. These flanges and the flared out head 31 give the desired degree of axial alignment of the plunger with the socket. The head is preferably shaped as shown to provide a short stud 32 around which the crimped-in edge of the fusee casing finds a steadyng seat. When a fusee is applied to the head and pushed into the socket, the cam-like lower face of the head first engages the latch ring, carrying it down, until the head passes through the ring whereupon the ring is further engaged by the fusee casing, which slips through it to final position.

Cross alignment of the head 31 and the outer rim of the socket, in the absence of a fusee, is secured by a pair of stiff wire rods 33, seated at their ends in the wall of the section 8 at the proper point to engage the flange 27. The rods are retained in their seats by the surrounding shell 9.

The plunger is resiliently pressed outwardly against the rods 33, or against a fusee if one is in the socket, by a coil spring 34, bearing at one end against the base flange 28 of the plunger, and seated snugly at the other end in the bore 36, formed in the handle beyond the bore 29, and against the annular shoulder 37, which is formed by the still smaller bore 38, extended toward the end of the handle to still further lighten it.

It is desirable to make the inside diameter of the socket of my fusee holder large enough to accommodate a small variation in the diameters of different fusees. There is a tendency therefore for the latch ring to press a loose fusee slightly out of axial alignment. This is corrected when desired by oppositely disposed buttons 41 and 42 so placed on the inside of the socket as shown in Fig. 1, as to provide a countervailing influence to maintain a substantial alignment of the fusee. To the extent that these buttons press into the casing, they assist in holding the fusee securely in the socket. A similar function is performed by the small rounded pins 43 which tend to center a fusee of loose fit in the socket, without preventing insertion of one making a tighter fit.

It will be clear from the above that my device as shown in Fig. 1 provides a convenient pin with which to loosen or move a coupling knuckle without endangering the hands. In this use, the head or socket portion is readily and safely grasped by the hands, the whole implement providing a lever of effective length for the application of force to the knuckle. At this time my implement also furnishes a steadyng hand hold in a position between the cars of recognized hazard.

If a fusee is to be used, it is only necessary to push the safe end into the socket, whereupon it may be lighted and handled, not only with greater facility and convenience but with marked lessening of danger from burns and ruined gloves and clothing. Upon exhaustion of the fusee, the burned out casing is ejected from the socket by the spring-pressed plunger when the slide is pulled back by the thumb to release the latch ring.

Because the danger of painful burns is largely removed, if a fusee is held in my holder while burning, there is less tendency to discard a burning fusee before it is exhausted; and consequently the use of my implement effects a material saving in the number of fusees consumed. Another valuable result flowing rather obviously from the safer and easier holding of a burning fusee is the transmission of better and plainer signals.

I claim:

A fusee holder comprising a socket of sufficient diameter to admit the end of a fusee, a plunger 35 slidable in the socket and having its outer end adjacent the open end of the socket, a spring compressed by inward movement of the plunger, a latch ring pivotally mounted in the socket and having an interior diameter sufficient to admit the end of the fusee, a spring interposed between socket and ring and tending to bias the ring relative to the socket, a button on the interior face of the socket and between the pivotal point of the ring and the open end of the socket, 45 a second button on the opposite side of the ring and diametrically opposite the first button, and means on the socket for moving the latch ring from a biased position into alignment with the socket.
